UNITED STATES PATENT OFFICE.

SAMUEL M. LANGSTON, OF WENONAH, NEW JERSEY.

METHOD OF MAKING SHINGLE STRIPS.

Application filed March 23, 1922. Serial No. 546,153.

To all whom it may concern:

Be it known that I, SAMUEL M. LANGSTON, a citizen of the United States, and resident of Wenonah, in the county of Gloucester 5 and State of New Jersey, have invented certain new and useful Improvements in Methods of Making Shingle Strips, of which the following is a specification.

This invention relates to the manufacture 10 of that type of multiple shingle or roofing strip which is made of paper, felt, asbestos, or other analogous flexible sheet material saturated or treated with asphalt, tar, pitch or other waterproofing composition and 15 coated on at least one surface with sand, grit, crushed slate, or other mineral or fire-proof material.

A common form of such multiple shingle is of a length several times the width and 20 provided with a plurality of notches or recesses in one of the longer edges, so as to form tabs each of a width corresponding to that of an individual shingle. The strips when laid in overlapping rows on the roof 25 have the tabs and notches exposed at the lower edge to give the general appearance of individual shingles.

The products of different manufacturers 30 vary as to the shape and configuration of these tabs or shingle-like projections, and as to the relative widths of the tabs and the notches or intervening spaces.

It is customary to cut such strips from sheet material which is continuously or intermittently fed from a roll, a saturating 35 and coating machine or other source of supply.

Many processes and machines have been 40 invented for making these multiple shingles. In some it has been proposed to use a sheet of a width corresponding to the length of the shingle strip with the strips extending transversely of the sheet, and the spacing between transverse cuts corresponding to the 45 width of a strip. In others it has been proposed to use a sheet of a width equal to a multiple of the width of a strip with the strips extending lengthwise of the sheet and slotted lengthwise between strips. There are 50 numerous advantages for the lengthwise arrangement of the strips in the sheet.

To make a clean transverse cut on continuously advancing material, the cutter, while operating, should advance with the material, and at substantially the same speed. The 55 greater the distance between transverse cuts

the more time there is for the cutter to complete its cycle of movement and come to position for the next cut. The smaller the number of cuts per unit of length of the advancing sheet, the faster can the sheet be advanced, whether the advance be continuous or intermittent, and the larger the number of shingles which can be produced in a given time.

The sheet material often varies slightly in width and therefore with the transverse arrangement of strips the strips will vary in length unless the sheet be trimmed to an exact width. Variation in length causes trouble in laying of the strips with tabs and recesses in accurate staggered relationship. With the strips extending lengthwise, a variation in the width of the sheet merely causes a variation in the width of the edge 75 strip or strips. This is of no material consequence as the extent to which the strips are overlapped when laid, may be varied to take care of variation in the width while maintaining the accurate staggering of recesses between tabs, and the uniform width of exposed tab ends.

If the sheet be of a width materially greater than the length of a standard shingle strip, but less than twice the length, the 85 traverse arrangement of strips may result in the waste of a trimmed off portion which may be of a width nearly equal to the length of a standard shingle strip, whereas with the lengthwise arrangement of strips, a 90 larger or smaller number of strips may be secured and the width of a possible waste portion will not exceed the width of a standard strip.

In spite of the forgoing advantages of reduction in number of transverse cuts per unit of length, faster speed of sheet delivery, limiting dimensional variations to strip width rather than length, and reducing the width of a possible waste strip if the sheet 100 be much too wide, the almost universal practice has been to cut the strips transversely of the sheet. Although the other arrangement has been tried from time to time, I do not know of a single instance of successful 105 commercial use of any process or machine prior to my invention, and in which a sheet is perforated or slotted and thereafter cut lengthwise and transversely to form shingle strips extending lengthwise of the sheet.

One of the principal difficulties which has prevented the use of the last mentioned ar-

angement, is the fact that as soon as the sheet is perforated or slotted at the proper points to form the recesses between the tabs, and the sheet is slitted, the resulting tabs and recesses of each strip extend in a direction at right angles to the direction of feed of the sheet. The tabs when unsupported at their free ends often droop or bend down, so that during the advance of the material they are liable to catch on or be folded under by parts of the machine with which they engage. The liability of bending the tabs is particularly great if the sheet material is fresh from the saturating and coating machine and still hot, as is usually the case. The supporting of the tabs as they advance to and pass beyond the chopper or other cut-off mechanism, involves serious mechanical difficulties. These difficulties, as well as others, have heretofore rendered preferable the cutting of the strips transversely of the sheet.

One object of my invention is to provide an improved method whereby I eliminate these difficulties which have been inherent in previously proposed methods of cutting the sheet into strips extending lengthwise thereof, and am able to cut the strips faster, more accurately and with less waste than is possible with strips extending transversely.

As one important feature, I first form transverse slots or apertures in the sheet in positions corresponding to the desired recesses in the shingle strips, and intermediate of the side edges of the sheet, so that each aperture or slot has a continuous periphery with no projecting parts which can bend out of the plane of the sheet, or fold over. I then cut the slotted or apertured sheet transversely into sections, each of a length corresponding to the length of a shingle strip, and as a final step, separately slit each such section to form the final product. As the tabs are not formed until the slitting from one slot or aperture to the next and as this slitting is the final step in the process, and while the product is leaving the machine, the strips may be slid or conveyed onto a carrier or stack, and the tabs supported without liability of their catching on the cut-off mechanism or other parts of the machine, as would be the case were the slitting performed before the transverse cutting.

By having all the slots or apertures intermediate of the edges of the sheet instead of in the edges of the sheet, there are no free end tabs until the slitting is done after the cut off, each tab has an accurately cut straight end rather than being formed of a raw edge of the sheet and variation of the width of the sheet does not vary the length or size of the tabs or recesses. Variation or irregularity in the width of the strip

formed along the edge portion of the sheet, comes on the edge of the strip opposite to the tabs, and this is covered in laying the roof.

As a further important feature, I employ the step of transversely severing the sheet in advance of a feeding or pulling means, so that the sheet is held taut where the cut-off action takes place, and greater accuracy in the length of the cut-off sections is secured, which is important in securing registry of the cut off with the previously formed slots or apertures.

I may form the slots or apertures by first cutting a row of pairs of parallel slits transversely of the sheet in positions corresponding to the opposite side edges of the desired slots or apertures, and thereafter as a separate step, connect the two slits of each pair at each end thereof by short, longitudinal cuts, and simultaneously remove the small pieces of material thus severed. The forming of the slots or recesses in this way permits a simplification of the construction and design of the cutting parts.

In the accompanying drawings:

Fig. 1 is a plan view of a sheet, successive portions from the right hand end toward the left hand end showing the action of successive steps of the method.

Fig. 2 is a diagrammatic view of machine parts which may be employed and properly driven and timed in respect to each other to carry out the method, and

Fig. 3 is a plan view of a section of a width to form four strips.

The material employed in my improved method may be that commonly employed in the manufacture of multiple shingles or roofing strips. This material in the form of a continuous sheet A may be delivered from a roll, or from a machine employed for saturating, coating, or otherwise treating the body or base portion of the sheet. The sheet is shown in Fig. 1 of a width substantially equal to three times the width of a single complete shingle strip. Obviously the method is not limited to this particular width, as the sheet may be of any width. If the sheet be materially wider than a multiple of the width of the strip, the waste portion will be less than the width of a strip. The first step in the cutting process is to form one or more rows of slots or apertures. This may be accomplished by first forming the desired number of rows of pairs of transversely extending slits A¹. The distance between the two slits of each pair is equal to the desired width of a recess in the completed shingle strip, the space between successive pairs is equal to the desired width of a shingle tab, and the length of each slit is equal to the depth of a recess or double the depth of the recess depending upon the

number of strips to be formed across the sheet. For an even number of strips, as shown in Fig. 3, the number of rows of slots may be one-half the number of strips to be formed, with each slot of a length equal to twice the depth of a recess between tabs. If there be an odd number of strips, as shown in Fig. 1, the slots of at least one row will be equal to the depth of the desired recesses.

I then connect the two slits, A¹, of each pair by longitudinally extending slits or cuts A², or otherwise punch out or remove the material between the two slits of each pair so as to form transversely extending apertures or slots A³. The slits A¹ may be formed by pairs of parallel knives 10, mounted on a roller 11, and coacting with a hardened steel surface of a roller 12. Other suitable slitting means might be employed, which would form the slits during the high speed lengthwise travel of the sheet. The slits A² may be formed by short longitudinally extending knives 13, on a roller 14, and acting against the surface of or into recesses in the surface of a roller 15. The removed portions may remain on the roller 15, and be separated therefrom by a suitable stripper 16.

30 The sheet next passes to a cut off mechanism which transversely severs the sheet into sections B. This cut off mechanism must be so designed that it may act on a rapidly traveling sheet without retarding the latter.

35 The mechanism somewhat diagrammatically illustrated may be substantially as shown in my prior Patent 1,359,076 issued November 16, 1920. This includes a pair of knives 17 and 18, one carried by an arm 19 pivoted

40 to swing about a fixed axis 20, and the other carried by an arm 21 pivoted to swing about an axis 22 on the first mentioned arm 19. The arm 21 has an extension 23 connected to the crank 24 of a crank disk

45 The rotation of the crank disk causes the knife 17 to move back and forth in the general direction of travel of the sheet, and also causes the knife 18 to travel not only lengthwise of the sheet, but toward and

50 from the knife 17. The crank may rotate continuously with a uniform or variable speed, or may stop and start after each cutting cycle. The proportioning of the parts

55 and the speed of the drive are such that at the instant the knives 17 and 18 come together and pass each other, they are traveling with the sheet at substantially the same speed as the latter. They do not slow up or start their return movement until after they have separated, so that the sheet is free at all times to advance at its uniform rate. Beyond the cut off knives are a pair of feed

rollers 26, 27, which are driven with a slightly higher surface speed than that of the travel of the body of the sheet. They may

slip on the sheet until the section is cut off, or they may have slip friction connections to a faster drive so that they speed up as soon as the section is free to advance independently of the sheet. Thus they take out 70 all slack in the sheet and hold taut the portion of the sheet passing between the two knives 17 and 18, and insure great accuracy in the cutting of the sheet into sections of uniform length. The feeding of the sheet 75 between the cutters which form the apertures or slots therein may be accomplished by feeding rollers 28 and 29 which have substantially the same rate of surface travel as the aperture forming cutters.

The feed rollers 26 and 27 act to jump each section B forwardly as soon as it is severed from the body of the sheet by the cut off mechanism, thus leaving a free space 80 between the ends of adjacent sections after they are cut off. This greatly facilitates the later stacking or conveying of the finished strips. The feed rollers 26-27 also act to deliver the cut off sections between pairs of slitters 30 and 31 which are so disposed transversely of the sheet as to slit each section lengthwise along lines so disposed that each row of apertures in the section is intersected by such a slit. If each section is to be cut into three strips C and the slots of 95 one row are of double the length of the other, then one pair of slitters would slit each section along a line C¹ intermediate of the ends of the longer slots, and the other pair of slitters would slit the sheet along a line C² 100 at one end of the apertures or slots of the other row, as shown in Fig. 1.

If the sheet is to be cut into an even number of strips, then all of the slots A³ may be of double length and certain slits C¹ bisect 105 these slots and other slits C² will be along lines midway between slots as shown in Fig. 3. The sections pass directly from the slitters to conveying means here shown, as a belt 32, and as both the slitters and the belt 110 may present smooth peripheries, an intermediate support 33 may be employed which fits close up to the slitter and conveyor and holds up the free ends of the tabs as soon as such tabs are formed by the longitudinal 115 slitting of the sections.

It will be noted that as an important feature of my invention the tabs are not formed until the last or final operation, and that there are no corners or shoulders which can 120 bend down or catch on any part of the machine during the progress of the material through the machine. As the slitting is the final operation, the tabs are not freed or completely formed until they are ready for 125 immediate delivery on to the conveying mechanism.

It will be noted that the feeding rollers 26, 27 which pull the sheet through between the transverse cut off mechanism 17, 18, act 130

- to advance all parts of the sheet crosswise thereof uniformly, inasmuch as the sheet at this time has not been split or slitted lengthwise. This is of material advantage in securing accuracy and uniformity in the length of the sections as if the sheet were slitted before or in advance of the cut off mechanism some strips might be drawn taut while others are comparatively slack, due to the irregularity in the thickness of the sheet and difference in the action of the feeding rollers on different strip sections. This advantage of uniformity of strip length by cutting transversely before slitting, is accomplished irrespective of whether the slots or apertures A³ be intermediate of the side edges of the sheet or extend inwardly from one or both edges to leave freely projecting tabs.
- It will of course be understood that the transverse cutting may be in alignment with either side of an aperture, or through the middle of an aperture, as shown, and that the sections B may be made to include a larger or smaller number of these apertures A³ depending upon the number of tabs and recesses along the length of each final shingle strip.

By taking all slack out of the portion of the sheet acted on by the cut off mechanism, I insure proper registry of the transverse cuts with the previously formed slots or apertures, which would not be the case if there could be slack of varying degrees between the slotting mechanism and the cut off mechanism.

Having thus described my invention, what I claim as new and desire to secure by Letters Patent is:—

1. The method of producing multiple shingle strips from a prepared sheet of roofing material of a width equaling the width of a plurality of said strips, each strip extending lengthwise of the sheet and having along one longitudinal edge thereof a plurality of notches or recesses and interposed tabs simulating the ends of individual shingles, said method consisting in forming apertures in the sheet in a row longitudinally of the sheet, and spaced at distances equal to the distances between the recesses or notches in the finished strip, severing said sheet transversely into sections each of a length corresponding to the length of a finished strip, and separately slitting each section lengthwise along a line intersecting said row of apertures.

2. The method of producing multiple shingle strips from a prepared sheet of roofing material of a width equaling the width of a plurality of said strips, each strip extending lengthwise of the sheet and having along one longitudinal edge thereof a plurality of narrow notches or recesses and interposed tabs simulating the ends of individual shingles, said method consisting in continuously advancing the sheet lengthwise, forming longitudinally of the sheet a row of apertures, cutting the sheet along transverse lines into sections and thereafter separately slitting each section lengthwise along a line intersecting the row of apertures.

3. The method of producing multiple shingle strips from a prepared sheet of roofing material of a width equaling the width of a plurality of said strips, each strip extending lengthwise of the sheet and having along one longitudinal edge thereof a plurality of narrow notches or recesses and interposed tabs simulating the ends of individual shingles, said method consisting in forming openings at uniform intervals along the length of the sheet intermediate of the side edges thereof, pulling the sheet taut, cutting the sheet transversely across the taut portion, and thereafter separately cutting each section lengthwise along a line intersecting the row of openings to form the roofing strips.

4. The method of producing multiple shingle strips from a prepared sheet of roofing material of a width equaling a multiple of the width of one of said strips, each strip extending lengthwise of the sheet and having along one longitudinal edge thereof a plurality of narrow notches or recesses and interposed tabs simulating the ends of individual shingles, said method consisting in forming openings at uniform intervals along the length of the sheet intermediate of the side edges thereof, pulling the sheet taut, cutting the sheet transversely across the taut portion, and thereafter separately advancing the cut-off sections at a more rapid rate than the rate of travel of the body of the sheet and cutting each section lengthwise along a line intersecting said openings.

5. The method of making shingle simulating strips of flexible material for roof covering which consists in providing a sheet sufficiently wide to make two or more strips, cutting a row of apertures at uniform intervals along the length of the sheet intermediate of the edges thereof, cutting the sheet transversely into sections, continuously advancing the sheet during the aperture-forming and section-cutting operations and separately advancing the cut-off sections and slitting them longitudinally into said strips.

6. The method of making shingle simulating strips of flexible material for roof covering which consists in providing a sheet sufficiently wide to make two or more strips, cutting apertures at uniform intervals along the length of the sheet, cutting the sheet transversely into sections while maintaining the sheet in taut condition, by the action of

feeding means disposed beyond the cutting means, continuously advancing the sheet during the aperture-forming and section cutting operations, and separately advancing 5 the cut off sections and slitting them longitudinally into said shingle strips.

7. The herein described method of making shingle strips which consists in forming an elongated strip of flexible material impregnated 10 with a water-proofing compound and covered with a mineral substance, forming longitudinal rows of apertures therein, severing the sheet transversely into sections, each having therein a plurality of apertures 15 of each row and cutting each section into strips along straight lines lengthwise thereof to produce strips each having a substantially straight longitudinal edge and a series of tabs and recesses along the opposite edge.

8. The herein described method of making prepared shingle strips, each strip presenting 20 a series of tabs, and narrower interposed recesses along one longitudinal edge thereof, said method consisting in cutting a longitudinally extending row of pairs of transversely extending slits in a sheet of prepared roofing material, cutting the sheet lengthwise to connect the two slits of each 25 pair at each end thereof, and permit removal of the severed pieces, cutting the sheet transversely into sections, and cutting 30 the sheet lengthwise to form the finished strips.

each section lengthwise to form the finished strips.

9. The herein described method of making 35 prepared shingle strips, each strip presenting a series of tabs, and narrower interposed recesses along one longitudinal edge thereof, said method consisting in cutting a longitudinally extending row of pairs of transversely 40 extending slits in a sheet of prepared roofing material, cutting the sheet lengthwise at spaced points to connect the two slits of each pair, and permit removal of the severed pieces, cutting the sheet transversely 45 into sections, cutting each section lengthwise to form the finished strips, and continuously advancing the sheet during all of said cutting operations.

10. The herein described method of preparing 50 shingle strips, each strip presenting a series of tabs and interposed recesses along one longitudinal edge thereof, said method consisting in cutting out portions of the sheet corresponding in position to the desired recesses, cutting the sheet transversely 55 into sections, cutting the separate successive sections lengthwise thereof, and continuously advancing the sheet, sections and strips during said cutting operations. 60

Signed at New York in the county of New York and State of New York this 20th day of March A. D. 1922.

SAMUEL M. LANGSTON.
